UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA.

MULTICOLOR MANIFOLDING SALES-BOOK.

1,151,655.

Specification of Letters Patent. Patented Aug. 31, 1915.

Application filed March 27, 1912. Serial No. 686,526.

To all whom it may concern:

Be it known that I, EDWARD KIRBY BOTTLE, a citizen of the United States, residing at Elmira, in the county of Chemung and State 5 of New York, have invented certain new and useful Improvements in Multicolor Manifolding Sales-Books, of which the following is a full, clear, and exact description, such as will enable others skilled in the art to which 10 it appertains to make and use the same.

This invention relates to manifolding devices, and with regard to certain more specific features thereof, to manifolding sales-books in which inscriptions or parts thereof 15 are reproduced in different colors.

In general, the objects of the present invention are to cause certain items to appear in different colors on the duplicates in the devices mentioned above; to render erasures 20 or changes more easily noticeable and diminish the chance of error. To effect these objects I provide original sales slips, each of which has a duplicate and which are grouped in the usual way, and between the original 25 and the duplicate I arrange two superposed copying sheets of different colors, the under one of which is cut away in certain desired places so that an entry upon the original will, without further attention by the clerk, 30 appear in different colors upon the duplicate. Of course it is within the scope of the invention to extend this arrangement to more than two sheets, but in general only 35 two sheets are desirable or necessary. In the preferred embodiment the sheets are black and red, but of course other colors could be used.

In the accompanying drawing, wherein is 40 shown one of many possible embodiments of my invention, Figure 1 is a perspective view of a complete device, and Fig. 2 is a plan view with the original leaf turned back to show the position and arrangement of the manifolding medium more clearly.

Similar reference characters refer to similar parts throughout both views of the drawing.

Referring now to the accompanying drawing, and more particularly to Fig. 1, there is 50 shown a pad comprising a plurality of sets of original and duplicate leaves 1 and 2, respectively. These leaves, as shown in the present embodiment, are of the well-known paragon fold; that is, the original leaves are

folded over the duplicate leaf and the duplicate portions are bound together at their ends by means of staples 3. The pad is inclosed within a suitable binding 4, extending downwardly and beneath the pad to form a back 5 whereby the pad may be inserted in 60 a holder. The original leaf 1 is connected directly with the duplicate leaf but is separated therefrom by line of perforations 6. The upper part of the duplicate leaf is also provided with perforations 7 in order that 65 it may be easily and quickly detached from the stub.

Bound with the leaves of the pad are a plurality of copying sheets, in the present case two, of different colors. The upper leaf 70 8 as herein shown is red, while the lower leaf 9 is of a different color, black for instance.

Each original and duplicate leaf is preferably provided with printed matter, such as indicated by the word "Cafe" or the name 75 and address of the concern using the book, as well as suitable lined or ruled spaces according to the use to which the book is adapted.

The book may be conveniently used as 80 follows:—The names of the dishes ordered are written at the left of each sheet, while the cost of each dish is written in the column at the right. It will be noted from the accompanying drawing that the black carbon 85 sheet 9 is below the sheet 8 and will reproduce in black upon the duplicate leaf 2 the name of the dish ordered, while the price of each dish will be reproduced in red in the column at the right, due to the overlapping 90 of the upper carbon sheet.

In the present embodiment the carbon sheet 9 is irregularly shaped or provided with a cut-away portion 10 to expose a square 11, marked "Total" upon the duplicate leaf, to the carbon surface of the sheet 8. This cut-away portion will be covered only by the red carbon sheet so that the total amount of the bill may be stamped 100 therein by the cashier and thus appear more prominently.

By providing manifolding sheets of two colors, one of which, 9, terminates adjacent the column in which the figures are placed 105 denoting the cost of the article ordered, there will be a marked distinction due to the contrasting colors between the name of the article and the cost thereof, thus eliminating the

possibility of confusing the figures with the terminating letter of a word. It will also be noted that if one attempts to erase a name or price in different colors they will tend to 5 rub and blend with one another, thus making detection of fraud a simple matter.

This embodiment of salesbook may be conveniently used as follows:—The transaction is recorded upon the upper surface of 10 the original leaf 1 in the usual manner, the name of the article being placed at the left and the price thereof in the columns at the right. Referring to Fig. 2, it will be seen that the former will appear in black upon 15 the duplicate leaf, while the price thereof will be transferred through the red sheet 8 to the corresponding columns on the duplicate leaf 2. By having the writing and figures in two colors, the tendency to confuse 20 one with the other is avoided. Also, it is more difficult to make changes and erasures without detection, as the colors will more or less rub together. On completing the transaction, the total is placed in the square 11 at 25 the upper left hand corner in order that the same may be more readily seen. The top set of leaves is then detached from the book by tearing it along the perforated line 7 and the original and duplicate leaves separated 30 from each other along the line of perforations 6. The original leaf is disposed of according to the rules of the establishment, while the duplicate leaf is presented to the purchaser.

35 It is thus seen that this invention provides a simple and inexpensive form of salesbook adapted to accomplish, among others, all of the objects and advantages above set forth.

As many changes could be made in the 40 above construction and many apparently

widely different embodiments of this invention could be made without departing from the scope thereof, it is intended that all matter contained in the above description or shown in the accompanying drawings shall 45 be interpreted as illustrative and not in a limiting sense. It is also to be understood that the language used in the following claims is intended to cover all of the generic and specific features of the invention herein 50 described and all statements of the scope of the invention, which, as a matter of language, might be said to fall therebetween.

Having described my invention, what I claim as new and desire to secure by Letters 55 Patent is:—

1. In a manifolding sales book, an original sales slip, a duplicate, and two superposed copying sheets of different colors between the slips, the under sheet being cut 60 away in desired places so that entries in different colors may be impressed upon the duplicate, as described.

2. In a manifolding sales book, an original sales slip, a duplicate, and a plurality 65 of superposed copying sheets of different colors between the slips, the upper sheet substantially covering the duplicate and the remainder of the copying sheets being cut away at desired places so that entries in different colors upon the duplicate are effected 70 by making ordinary entries upon the original, as described.

In testimony whereof I affix my signature, in the presence of two witnesses.

EDWARD KIRBY BOTTLE.
